UNITED STATES PATENT OFFICE.

HARRY C. GOODRICH, OF CHICAGO, ILLINOIS.

TUCK-CREASER FOR SEWING-MACHINES.

SPECIFICATION forming part of Letters Patent No. 275,820, dated April 17, 1883.

Application filed August 8, 1881. (Model.)

To all whom it may concern:

Be it known that I, HARRY C. GOODRICH, residing at Chicago, in the county of Cook and State of Illinois, and a citizen of the United States, have invented a new and useful Improvement in Tuck-Creasers for Sewing-Machines, of which the following is a full description, reference being had to the accompanying drawings, in which—

10 Figure 1 is a top or plan view; Fig. 2, a side elevation; Fig. 3, a detail, being an under side view, showing principally the rear end of the vibrating arm, the spring or spring-plate, the support for the arm, and the rear end of the adjusting-plate; Fig. 4, an end elevation of the parts carrying the creasing device, showing the adjusting-plate in section; Fig. 5, a detail showing the bearing for the hinged or pivoted arm carrying the creasing devices; 15 Fig. 6, detached views of the secondary arm and the plate or base to which it is hinged, and Fig. 7 a central longitudinal sectional view taken through the hinged arm.

This invention relates to that class of tuck-creasers for sewing-machines in which a vibrating arm having a descending movement given thereto by the descent of the needle-bar, to which it is connected, in descending engages a secondary arm carrying a creasing 20 device, and causes such device to act in conjunction with a blade and form a crease or mark on the material, the material passing between the creasing device and the blade, and the pressure of the creasing device thereon producing the crease or mark. In this 25 class of tuck-creasers the vibrating arm and the secondary arm each have a spring action, by which they return to their normal positions on the ascent of the needle-bar, and the pressure exerted by the creasing device is derived from the force produced by the descent of such bar.

The principal and primary objects of this invention are to render the action of the 30 creasing device more effective and reliable in use, and to insure the production of a clean and distinct crease or mark. This I accomplish by the construction and arrangement of parts, which I will now proceed to describe in 35 detail, afterward pointing out the improvements in the claims.

In the drawings, A represents the vibrating arm; B, the flat spring or spring-plate; B', the plate carrying or supporting the secondary arm; C, the support for the vibrating arm; D, the sliding plate; D', the lateral extension or arm of the plate D, carrying the blade; E, the base-plate; F, the plate for adjusting the parts for the desired width of tuck; G, the secondary arm, carrying the creasing device; H, the hinged or pivoted link-support for the creasing device; a, the journal or pivot of the vibrating arm; a' a'', the lifting lever or arm; b, the slot in the end of the flat spring or spring-plate; c, the socket or bearing of a; 40 d, the rivets for attaching the support, flat spring or spring-plate, and the sliding plate together; e, the guides for maintaining the sliding plate in position; f, the thumb or set screw for attaching the device to the bed-plate of the machine; f', the adjusting-slot in the plate F; f'', the thumb or set screw for locking the plate F when adjusted; g, the ears or bearings for attachment of the arm G; g', the base-plate of the ears or bearings g; h, the 45 creasing roller or device; i, the blade; j, the catch or lip for holding the material; k, the stops on the sides of the arm G; l, the stops on the ears g; m, the return-spring for the link H; n, the ears or bearings for attachment of the link H.

The vibrating arm A may be made of a piece of brass wire or other suitable material, and the flat spring or spring-plate B, support C for the arm A, supporting-plate B' for the arm, 50 sliding plate D, base-plate E, crease-adjusting plate F, and secondary arm G may be made of sheet-brass or other suitable material. The rear end of the arm A has a portion, a, bent at right angles to the body of the arm, 55 which forms a journal or pivot for the arm, and this portion has a return given thereto, which forms an arm or lever, a', by means of which the vibrating arm is raised through the action of the flat spring or spring-plate B, 60 the outer or free end of which engages and bears against the under face of the lever or arm a', and acts to raise such lever or arm and throw the vibrating arm up after each depression.

The flat spring or spring-plate B is attached at its inner end by rivets or otherwise to the

rear end of the sliding plate, and is curved or bent outward and upward after it leaves the plate to give it the required spring action and bring its free end into engagement with the lever or arm a' . As shown, the free end of this flat spring or spring-plate is provided with a notch or slot, b , and the outer end of the arm or lever a' is bent or turned to form a projection or end, a'' , to enter the slot b , the object being to prevent side-play or end movement of a' from occurring and cause a displacement of the parts. This side movement or end-play can be prevented in other ways, as by forming collars on a' each side of the support therefor, or by providing the support with a slot to receive the end a'' , or with ears or guideways, between which the end a'' is free to move; or the flat spring or spring-plate can be left to act on the lever or arm a' without connection between the parts, and attain the desired result of an upward pressure to return the arm A .

As shown, the plate B' , which carries the secondary arm, is an extension of the plate forming the spring; but it may be an independent piece, if desired, suitably attached to the sliding or adjusting plate at its rear end, so as to leave its front end free, in the usual manner.

The support C is located above the spring or spring-plate, and is bent or curved to correspond to or nearly to the curvation of the spring or spring-plate, and its inner end and the lower end of the spring or spring-plate are united by rivets d , one of which rivets, as shown, passes through the plate D and furnishes the means for attaching or uniting these parts together. The outer end of the support C extends over and beyond the outer end of the spring or spring-plate, and has ears or pendants e , which form bearings for the journal or pivot a . This support C also forms a stop, against the face of which the arm or lever a' strikes when returned by the action of the spring or spring-plate, thereby preventing disengagement of the arm or lever from contact with the spring or spring-plate.

The plate D has at its forward end a side arm or extension, D' , on which is located the blade i , in the manner usual for other forms of tuck-markers, and the main portion or body of this plate D has a longitudinal slot, f' , for adjusting purposes, through which slot the set-screw f'' passes to clamp the plate to the base or guide plate. This plate D carries the operating devices, the plate B' , spring or spring-plate B , and support C , being attached thereto, so that the relation of the devices will not be changed in adjusting for different widths of tucks.

The base or guide plate E is located beneath the sliding plate D , which rests thereon, and is somewhat wider than such plate, and has the portion which projects beyond the side of the plate D provided with a longitudinal slot (shown by dotted lines, Fig. 1) for the passage of the set-screw f , by means of which the plate

E is secured to the bed-plate of the machine in the usual manner. The front end of this plate E is provided with an upwardly-turned edge or flange, e , having suitable openings for the passage of the sliding plate D and the width-adjusting plate F , which flange forms a guide, against which the edge of the cloth will travel and cause it to run straight. The width-adjusting plate is located on top of the plate E , and has at its rear end an opening which coincides with the slot in the plate E for the passage of the set-screw f , by means of which the plate is attached to the plate E , and its front end is provided with a tongue or extension on which are lines and numbers, by means of which and corresponding lines and numbers on the sliding plate D the desired width of tuck is obtained by adjusting the plates D F in the usual manner. This plate F has a side extension or portion which projects over the plate D , and is provided with a longitudinal slot which coincides with the slot f' in the plate D for attaching the plates by the set-screw f'' . To adjust the plate D for any desired width of tuck, the set-screws f'' are loosened and the plate D moved forward or back, as required, and the plate F moved accordingly and in the usual manner.

The secondary arm G is pivoted at its rear end between ears or lugs g on the forward end of the plate or arm B' , which ears or lugs, as shown, are formed on a plate or base, g' , which can be clasped around or on or otherwise secured to the end of B' ; or the ears or lugs can be secured directly to the face of B' in some other suitable manner. The front edge or face of these ears or lugs is rounded off on an arc of a circle struck from the pivot-center as a center, so as to allow the arm G to have a free movement in a downward direction and a free return or movement to the extent required to leave a sufficient space between the creasing device and the blade i . The upward movement is limited by stops l , located one on the upper edge of each lug or bearing g , against the face of which shoulders or stops k on the arm G will strike, the stops k being arranged and located in such relation to each other as to come in contact when the arm has returned or is raised the distance required for the creasing device to clear the blade and allow the cloth to feed. These stops prevent the arm G from being thrown over out of the way of the descent of the vibrating arm A , and instead of forming the stops k , as shown, by turning down a side lip or catch on each side of the arm G , these stops can be formed by the end of the arm itself by making the body wider than the space between the bearings, so as to leave shoulders on each side.

The link or pendant H , which carries the creasing device, is pivoted at its upper end between ears n on the arm G and depends from such arm, so as to bring the creasing device, when the arm G is at rest, above and over the cloth and blade, to be pressed down and form the crease or mark between the creas-

ing device and the blade. This arm or pendant *H* hangs down from the arm *G* with a forward inclination, as shown, and on its lower end is suitably journaled a creasing wheel or device, *h*, which, as the arm *G* is depressed, will travel over the blade *i* in a forward direction. The ears *n* are so located in relation to the blade *i* as to be back of or in line, or nearly so, with the rear end of such blade, and the forward inclination of the link from its point of pivot is such as to bring the creasing roller or device when the parts are at rest with its center near the inner end of the blade *i*, so that such device will travel the length, or nearly so, of the blade in making the crease or mark, the center of the pivot or journal for the creasing device being forward of the center of the pivot for the link, so that the roller will have a perfect freedom of movement and the two pivotal points will not get in line and lock the link *H* and arm *G* and prevent a downward movement of the arm.

The spring *m* is attached at its rear end to the under face of the arm *G*, and its front end is made to engage with the upper end of the link *H*. This spring acts to return the link to its normal position on the ascent of the arm *G*, and its relation to the link is such as to allow a free forward or outward movement of the link from the descent of the arm, the force with which the spring acts being simply sufficient to return the link and carry the creaser backward or inward without offering any great amount of resistance to the forward or outward movement, in attaining which result it is assisted by the inclination of the link *H* and the advantage of leverage which the link has in moving forward, the force being applied at the lower end of the link and the resistance being at the upper end of the link close to the pivot, which forms the fulcrum. Instead of using a flat bearing-spring, *m*, as shown, a coil or rubber spring might be used, located and arranged to bear against or on the upper end of the link and throw its lower end backward or inward, and instead of giving the link a forward inclination, as shown, such link might have a backward inclination, in which case the creasing device would start from the front of the blade and travel backward thereover, the link being hung farther forward on the arm *G* in this case, and the center of the pivot for the creasing device being back of the center of the pivot of the link.

The operation will be readily understood. As the arm *A* descends with the needle its front end will come in contact with the front end of the arm *G* and carry such arm downward, and this downward movement of the arm *G* carries the outer end of the link *H* forward or backward, according to its inclination, carrying with it the creasing device, which has been brought in contact with the blade by the downward movement of the arm *G*, and causing such device to travel the length of the blade over the cloth or material, producing by its action, in conjunction with the blade, a mark or crease in the cloth.

On the upward movement of the needle the arm *A* is carried up, releasing the pressure from the arm *G* and leaving such arm free to be returned to its normal condition, which return is secured by the action of the spring *m*, which returns the lower end of the link to its normal position, raising the arm *G* by the contact of the roller *h* or creasing device with the cloth on its return movement. These movements of the arms *A* *G* and creasing device will follow each descent and ascent, producing a continuous crease or mark for the tuck. The width of tuck is to be adjusted, as usual, by the gage-marks on the plates.

By hanging the arm *A* at its attached end in bearings on a stationary support and making such end crank-shaped, to be engaged and acted on by a spring or spring-plate to return the arm, it will be seen that the only resistance offered to the descent of the arm is the resistance of the spring-plate, and this resistance will not be very great, owing to the fact that the resistance is close to the fulcrum and the power is applied at a point considerably removed therefrom, by which arrangement but a slight amount of power is required to overcome the resistance, leaving nearly the entire amount of power free to be applied to the arm *G* and give the creasing device an increased pressure.

By hanging the arm *G* at its attached end on a pivot or pivotal connection such arm acts entirely free and independent of the supporting-plate *B*, and no force is expended in overcoming the resistance of the plate *B'* to the downward movement of the arm *G*. The plate *B'* is left free and natural, and will not be twisted or turned. The arm *G* offers no resistance to the downward movement of the needle-bar, and the force of the downward movement passes to the creasing device, increasing the effectiveness of such device. The creasing device receives the full benefit of the downward stroke and pressure of the needle-bar, and is thereby given an increased pressure, and the operation of producing a clear and distinct mark is more positively assured.

By supporting the creasing device by an arm or pendant having an angle of inclination such device is free to act and no impediment or resistance is offered, the link swinging readily at its lower end with the downward movement of the arm *G*, and traveling the creasing device over the cloth or material.

By pivoting the actuating-lever *A* and having it subjected to but a small resistance, as described, and by pivoting the secondary arm *G* and having it free and independent of the supporting-arm *B'*, and by carrying the creasing device on a link, as described, it will be seen that the only resistance to be overcome is that of the spring or spring-plate *B'* and that of the spring *m*, and that such resistance is but very slight, owing to the location of the fulcrums in each instance in relation to the power and the resistance, by which means the creasing device receives nearly all of the force

of the needle-bar, so that such force is applied where it is most needed, directly on the creasing device, giving such device a reliable, effective, and positive action.

5. What I claim as new, and desire to secure by Letters Patent, is as follows:

1. In a tuck-marker, the combination, with the pivoted vibrating arm A, of the longitudinal plate B', prolonged at the rear end into an upwardly-bent flat spring, B, the end of which acts on the vibrating arm to restore it to an elevated position, substantially as described.
2. In a tuck-creasing device for sewing-machines, a vibrating arm, A, having its rear end bent to form a bearing portion, a; and a lever or arm, a' a'', in combination with a flat spring or spring-arm, B, bearing against the rear end of the arm, substantially as and for the purposes specified.
3. In a tuck-creasing device for sewing-machines, a vibrating arm, A, having its rear end bent to form a bearing portion, a, and a lever or arm, a' a'', in combination with a flat spring or spring-plate, B, having a slot, b, and a support, C, having the bearings c, substantially as and for the purposes specified.
4. The combination, with the creasing-edge and the vibrating arm, of a plate or arm, B', provided at its forward end with the plate or base g', having ears g and stops l, the arm G, pivoted between said ears and having the stops k at its sides, the spring m, and the link H, carrying a creasing device, substantially as described.
5. The combination, with the creasing-edge and vibrating arm, of the plate B, the arm G,

having a hinged connection at one end with the outer end of the plate, the depending link H, pivoted to the outer portion of the hinged arm and carrying a creasing device, 40 and the flat spring m, having one end connected with the under side of the said arm adjacent to or at its hinged end, and its other end acting on a part of the link, substantially as shown and described. 45

6. In a tuck-creasing device for sewing-machines, the combination of the hinged or pivoted arm G, having stops k, and hinged or pivoted link H, carrying a creasing device, with the plate or arm B', and bearings g, having the stops l, substantially as and for the purposes specified. 50

7. In a tuck-creasing device for sewing-machines, the combination of the hinged or pivoted arm G, having stops k, hinged or pivoted link H, carrying a creasing device, and spring m, with the plate or arm B', and bearing g, having stops l, substantially as and for the purposes specified. 55

8. In a tuck-creasing device for sewing-machines, a vibrating arm, A, having its rear end bent to form a bearing portion, a, and a lever or arm, a' a'', flat spring or spring-plate B, having slot b, and support C, in combination with a hinged or pivoted arm, G, hinged or pivoted link H, carrying a creasing device, plate or arm B', and bearing g, substantially as and for the purposes specified. 60
